US0D1102106S

(12) **United States Design Patent** (10) **Patent No.:** **US D1,102,106 S**
(45) **Date of Patent:** **** Nov. 18, 2025**

(54) **FOOTWEAR**

- (71) Applicant: **Crocs, Inc.**, Broomfield, CO (US)
(72) Inventor: **Alexander Jacob Mayhew**, Denver, CO (US)
(73) Assignee: **Crocs, Inc.**, Broomfield, CO (US)
(**) Term: **15 Years**
(21) Appl. No.: **29/802,896**
(22) Filed: **Aug. 9, 2021**

Related U.S. Application Data

- (63) Continuation-in-part of application No. 29/802,200, filed on Aug. 3, 2021, now abandoned, and a continuation-in-part of application No. 29/786,624, filed on Jun. 1, 2021, now Pat. No. Des. 1,073,271.

CLAIM

The ornamental design for footwear as shown and described.

DESCRIPTION

FIG. 1 is a top perspective view of footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1-7 that are overlaid with a white transparent mask bounded by broken lines represent portions that form no part of the claimed design.

1 Claim, 7 Drawing Sheets
